UNITED STATES PATENT OFFICE

107,800

DESIGN FOR CHESSMEN

George W. Slater, East Akron, Ohio

Application May 4, 1937, Serial No. 69,145

Term of patent 7 years

To all whom it may concern:

Be it known that I, George W. Slater, a citizen of the United States of America, residing at East Akron, in the county of Summit and State of Ohio, have invented a new, original, and ornamental Design for Chessmen, of which the following is a specification, reference being had to the accompanying drawing, wherein:

Figs. 1, 2, 3, 4, 5, and 6 are perspective views of the chessmen showing my new design.

I claim:—

The ornamental design for chessmen as shown.

GEORGE W. SLATER.
